UNITED STATES PATENT OFFICE

154,823

DESIGN FOR A TRUCK MOUNTED ELEVATING TOWER

Harold A. Wagner and Gustave H. Wagner,
Portland, Oreg.

Application September 3, 1946, Serial No. 133,026

Term of patent 14 years

(Cl. D14—3)

To all whom it may concern:

Be it known that we, Harold A. Wagner and Gustave H. Wagner, citizens of the United States, residing at Portland, in the county of Multnomah, State of Oregon, have invented a new, original, and ornamental Design for a Truck Mounted Elevating Tower, of which the following is a specification, reference being had to the accompanying drawings, forming a part thereof.

In the drawings Fig. 1 is a side elevational view of the truck mounted elevating tower showing our new design as it appears when in the inoperative position; Fig. 2 is a plan view of the apparatus illustrated in Fig. 1; Fig. 3 is a side elevational view of the apparatus showing the tower in the upright or operative position; Fig. 4 is a front view of the apparatus in the position as shown in Fig. 1; Fig. 5 is a rear view of the

apparatus as shown in Fig. 1, and Fig. 6 is a perspective view of the apparatus showing the tower in the upright position.

We claim:

The ornamental design for a truck mounted elevating tower, substantially as shown.

HAROLD A. WAGNER.
GUSTAVE H. WAGNER.
